UNITED STATES PATENT OFFICE.

WILLIAM H. SOMMER, OF PEORIA, ILLINOIS.

COLLECTING BOX FOR WIRE-DRAWING BLOCKS.

Original application filed May 11, 1923, Serial No. 638,265. Divided and this application filed July 14, 1924. Serial No. 726,059.

This invention has reference to a collecting box for wire-drawing-blocks and it has for its principal object to provide a closure for housing a drawing-block and the wire-drawing-die associated therewith, or at least the delivery end thereof, in which is collected the smoke, dust and gases created by the drawing operation to carry off such smoke, dust and gases through a flue in communication with the collecting box so as to prevent the distribution of such smoke, dust and gases within drawing-room in which such block or blocks are located; whereby the atmosphere in such drawing room is kept comparatively free of the smoke, dust and gases and health conditions thereby improved for the men who are engaged in such drawing operations.

The invention has for a further object to provide a collecting box for wire-drawing-blocks which is designed to collect smoke, dust and gases created by the drawing operation and to eject the same from the wire-drawing-room through a suitable flue, such collecting box also removing the hazard due to the wire-drawing operation by preventing the wire drawer from getting his fingers, hands or arms caught in the wire, and practically compelling the wire drawer to stop the block when inspecting the drawn wire in the event the assumption arises that the drawn wire is not smooth or of standard gauge, and to prevent the whipping of the tail end of the wire as a bundle is completed by retaining the tail end of the wire within the collecting box, thereby preventing the otherwise whipped wire being thrown against the operator and endangering his body or limbs.

The invention has for a further object to provide a collecting box for wire-drawing-blocks designed to collect dust, smoke and gases created by the wire-drawing operation, and to expel the same therefrom through a flue leading into the open air; said box also collecting and expelling through the flue the heat due to the wire-drawing operation within the box and thereby reducing the temperature within the drawing-room which is intensified by the use of a multiplicity of blocks without the provision of a box of this character, resulting in working conditions being uncomfortable to the men particularly during the warm weather.

A further object of the invention is the

provision of such a collecting box for wire-drawing-blocks which may comprise an individual box for each block connected with an individual flue, as herein shown, or in the provision of a housing divided into compartments, as illustrated in the original application hereof, bearing Serial No. 638,265, one for each block and each box connected with a discharging flue.

In the application of the invention the same may be applied to drawing-blocks with or without stripping-mechanism for the bundles of drawn wire, provision being made for the removal and replacement of such stripping-mechanism in the event of the use of same.

This application is a division of the application filed by me May 11, 1923, bearing Serial No. 638,265, now Patent No. 1,570,711, issued January 26, 1926.

That the invention may be more fully understood, reference is had to the accompanying drawings forming a part of this application, illustrating a preferred embodiment of the invention in which:

Fig. 1 is a front elevation partly broken away showing a part of a wire-drawing-bench with wire-drawing-blocks thereon in dotted lines and my collecting box applied thereto;

Fig. 2 is a plan view of Fig. 1;

Fig. 3 is a front elevation of a part of a wire-drawing-bench and in dotted lines a drawing-block thereon enclosed within a collecting box, such construction contemplating an individual collecting box for each drawing block;

Fig. 4 is a plan view of Fig. 3;

Fig. 5 is an end elevation of Fig. 3 looking in at the right hand end thereof and in cross-section showing the trunk with which the flues from the boxes are connected;

Fig. 6 is a detailed sectional view of a portion of the collecting box and cover in Fig. 5, and

Fig. 7 is an elevation showing a stripping-mechanism with a drawn bundle of wire thereon and the cover for the box shown in Fig. 5, raising and lowering means being illustrated to show how the cover for the collecting box is removed and replaced using the stripping-mechanism.

Like characters of reference denote corresponding parts throughout the figures.

Inasmuch as I have preferred to show the

invention applied to a wire-drawing-bench where the drawing-blocks are equipped with a stripping-mechanism, reference may be had to the patent issued to John Sommer, May 2, 1922, for stripping-mechanism for wire-drawing-blocks No. 1,414,380, which is the character of stripping-mechanism illustrated in dotted lines in the drawings forming a part of this application.

10 In view of the knowledge existing with those skilled in the art to which this invention appertains as to the construction of wire-drawing-benches and wire-drawing-blocks thereon, as well as the means for rotating and controlling the rotation of such blocks and the drawing-dies, I have not thought it necessary to more than outline such structures, as their details of construction and mode of operation form no part of 15 the present invention. Suffice it to say that 20 1 designates a drawing-bench, 2 the drawing-blocks thereon, each of which in this instance is provided or equipped with a stripping-mechanism 4 of the characters shown 25 and described in the aforementioned Sommer Patent No. 1,414,380, and dies 5, shown in dotted lines in Figure 2.

Reference being had to Figs. 3 to 7 both 30 inclusive the collecting boxes 28 are individual closures, or housings for the drawing-blocks 4. These are preferably round in shape, to conform to the drawing blocks, as shown with the mouth-piece 29 into which the drawing-die 5 is inserted, as shown in 35 dotted lines in Fig. 4; the box being permanently secured on the drawing bench and having an open top arranged to be closed by a lid or cover 30 which is removable with the stripping-mechanism. With this type 40 of box it is preferable to use a stripping-mechanism. The front portion of the wall of the box 28 has an opening 31 to enable the wire drawer, when the rod or wire has been passed through the die 5 to secure the 45 end thereof to the block, a portion of which opening is closed by the hinged cover 32. Connected with each box 28 is a flue 33, which may convey the smoke, dust and gases, as well as the heat from the box to the open 50 air direct, or the several flues connected with a trunk line 25.

The cover 30 for the box 28 is provided 55 with the diametrically disposed openings 34, see Fig. 4, through which is passed a member of the stripping-mechanism to which the lifting means may have connection and washers or gaskets 35 may be provided to give a tight fit over these openings, said cover 30 is also provided with an opening 60 36 through which may project a crank-arm or lever, not shown, which operates the gripping means within the drawing-block for connecting the rod or wire thereto to be drawn.

65 In Fig. 7 a lifting means is shown connect-

ed with the stripping mechanism and the latter with the cover 30 removed from the collecting box 28 and off of the wire-drawing-block 4 to remove therefrom the drawn bundle of wire. 70

Anyone who is familiar with wire-drawing operations knows that such occupation is a hazardous occupation, due sometimes to conditions over which no one in particular has any control, and in many instances due 75 to the inexperience of wire-drawers or because of carelessness on the part of both inexperienced and experienced wire drawers. The collecting box which I have devised is therefore not only a means of carrying off 80 the smoke, dust and gases due to the wire drawing operation but will prevent wire drawers from getting their fingers, hands and arms caught in the drawn wire at the block and doing them bodily injury, as well 85 as preventing the tail ends of the drawn-wire leaving the dies from whipping around and doing bodily injury to the wire drawers. Whatever whipping action there may be is confined within the collecting box, as 90 it is believed will be understood.

What I claim is:—

1. In combination with a wire-drawing block and stripping mechanism therefor, a collection and safety box enclosing said block and the stripping mechanism, means in communication with the box interior for carrying off the smoke, gases and dust therefrom, and a removable lid for said box having a part thereof engageable with the stripping mechanism of the block whereby to simultaneously remove the lid with the stripping mechanism. 95

2. In combination with a wire-drawing block and stripping mechanism therefor, a collection and safety box enclosing said block and the stripping mechanism, means in communication with the box interior for carrying off the smoke, gases and dust therefrom, and a removable lid for said box having a pair of diametrically opposed openings therethrough to receive parts of the stripping mechanism and to permit such parts to engage the lid whereby to simultaneously remove the lid with the stripping mechanism. 105 110

3. In combination with a wire-drawing block and stripping mechanism therefor, a collection and safety box enclosing said block and the stripping mechanism, means in communication with the box interior for carrying off the smoke, gases and dust therefrom, and a removable lid for said box having a series of openings therethrough, the stripping mechanism having parts thereof extending through the openings and engageable with the lid whereby to effect simultaneous removal of the lid with the stripping mechanism. 120 125

4. In combination with a wire-drawing

block, a collection and safety box enclosing the block, means to convey smoke, dust and gases from the box interior, said box having a mouth to admit the drawing-die and having a passage to enable the operator to secure the end of the wire from the drawing-die to the block, and a displaceable cover for the passage.

5. In combination with a wire-drawing block, a collection and safety box enclosing the block, means to convey smoke, dust and gases from the box interior, said box having a mouth to admit the drawing-die and having a passage to enable the operator to secure the end of the wire from the drawing-die to the block, and a hinged cover for partially closing the passage.

6. In combination with a bed, a wire-drawing block thereon, a collection and safety box on the bed enclosing the block, means to convey smoke, dust and gases from the box interior, said box having a mouth opening onto the bed to allow the drawing die to be seated on the bed and slid into the mouth, and a removable lid for the box.

7. In combination with a bed, a wire-

drawing block thereon, a collection and safety box on the bed enclosing the block, means to convey smoke, dust and gases from the box interior, said box having a mouth opening onto the bed to allow the drawing die to be seated on the bed and slid into the mouth and having a passage to enable the operator to secure the end of the wire from the drawing die to the block, and a removable top for the box.

8. In combination with a wire-drawing block, equipped with stripping mechanism, of a collecting and safety box for enclosing said block and stripping mechanism having an opening therein for the passage of a wire from a drawing-die and adapted to collect smoke, dust and gases created by the drawing operation, a draft flue in communication with the interior of said box for carrying the smoke, dust and gases therefrom and a removable lid for said box, said lid having a part engageable with the stripping mechanism of the block whereby to simultaneously remove the lid with stripping mechanism.

WILLIAM H. SOMMER.
